UNITED STATES PATENT OFFICE.

MAURICE HOWELL UTLEY AND ALEXANDER ROSS, OF MONTREAL, CANADA.

IMPROVEMENT IN ELECTRO-MAGNETIC MOTORS.

Specification forming part of Letters Patent No. 119,899, dated October 10, 1871.

To all whom it may concern:

Be it known that we, MAURICE HOWELL UTLEY, of the city of Montreal, in the district of Montreal, in the Province of Quebec, doctor of medicine, and ALEXANDER ROSS, of same place, optician, have invented new and useful Improvements on Double-action Electro-Magnetic Motor; and we do hereby declare that the following is a full, clear, and exact description of the construction and operation of the same, reference being had to the annexed drawing, where—

Figure 1 represents an elevation of the motor with part of the outer set of magnets removed. Fig. 2 represents a vertical section of Fig. 1. Figs. 3, 4, and 5 represent horizontal sections on line A, B, Figs. 1 and 2. Fig. 6 represents a sectional plan of compound commutator. Fig. 7 represents an elevation of same. Fig. 8 represents a detail of electro-magnet. Fig. 9 represents a plan of simple commutator-switch. Fig. 10 represents a section of condenser. Fig. 11 represents a section of governor.

The object of the present invention is to produce a double-action electro-magnetic motor that may be made available for many purposes where rotary motion is required, including generally all those for which steam power is at present used, and many others for which steam power cannot easily be adapted; as, for example, the acting simultaneously upon all the brakes of a railway train by the mere movement of a handle by the finger of any of the persons in charge of the train.

In the drawing hereunto annexed similar letters of reference indicate like parts.

a are two disks, of metal, forming the ends of a frame-work; these are attached together by three or more pillars, *a*¹, as desired. To these are attached two rings, *b*¹, by means of any suitable lugs, *b*², formed on the pillars; or they may be attached in any desired or ordinary manner. In the center of the disks *a* a set-screw, *b*³, in each is provided, arranged with jam-nuts for adjusting and securing them in their required positions to hold the shaft *c* forming the axis of the machine. This is done by providing the shaft with male conical ends, and the set-screws with corresponding matrical ends, as shown in the drawing, Figs. 1 and 2, this being the form of bearing giving the least frictional resistance; but, if required, the bearings may be made in any other suitable or ordinary form, as will be

the case when the ends of the shaft require to be extended. Although but two rings, *b*¹, and other parts, which will be hereinafter described, are shown in the drawing, their number may be increased as desired, or as found most beneficial to the particular purpose for which the machine is applied. On the shaft *c* a cylinder of brass, *c*¹, is secured by means of a diaphragm, *c*², in the center of the cylinder, and which may be cast in one with it, the cylinder *c*¹ extending on both sides of the diaphragm a sufficient extent to form a surface for attaching two sets of magnets, *d*¹. In the periphery of the cylinder *c*¹ plates *d*², of soft iron, are dovetailed or otherwise secured; there being two provided for each magnet, and inserted at equal distances around the periphery of the cylinder, being turned to a true surface with it. At the back of the plates *d*² openings are formed in the cylinder, to allow the ends of the magnet core to pass and rest upon the plates *d*², to which they are attached by screws; thus the plates become the poles of the magnets. It will, therefore, be readily understood that *e* are the cores of the magnets, of soft iron, and *e*¹ the ordinary insulated copper wire wound around them in the usual way of forming an electro-magnet. The wire *e*¹ in this case is continuous in each series of magnets, *d*¹, the current of electricity entering on one coil, traversing in succession the whole, and leaving when it has completed the circuit of magnets. To the rings *b*¹ magnets *f*¹, of a similar character to those above described, as *d*¹, are attached, being equal in number to them, and disposed in the manner indicated in the drawing at equal distances, and their poles terminated in plates *f*², corresponding to those *d*². These are situated at equal distances in a circle a little larger than the diameter of the cylinder *c*¹, so that the two do not touch; but otherwise they will be brought as near as possible. In the arrangement of the two series of magnets *d*¹, those marked *d* may be said to be placed in the position shown in Fig. 5, while those marked *d*¹ are in the position shown in Fig. 3 or 4; or, in other words, when the poles of the upper series *d* are opposite the poles of the series *f*, the poles of the series *d*¹ are intermediate with the poles of the series *f*¹. This is to obviate the possibility of the machine stopping in such a position that the switching on of the battery would fail to start it without other appliances, (as in the dead-

center of a single crank steam-engine;) and in case of using a greater number of series of magnets, they will be so arranged that the poles of no two series will be in the same position at the same time with regard to the series of magnets.

The compound commutators, by means of which the direction of the current is changed exactly at the points required in the series of magnets d^1 , are shown in Figs. 1, 2, 6, and 7, and are each constructed as follows: On the shaft c and in the position shown in the drawing, Figs. 1 and 2, a piece of ebonite or other insulating material, g , is placed, being secured to it; this is surmounted with two pieces of suitable metal, g^1 g^2 , which do not touch each other in any part; these form the terminals of the wire e^1 , one end being attached to g^1 and the other to g^2 , the necessary insulation from every other part of the machine being provided in the ordinary manner. The terminals g^1 g^2 having longitudinally-projecting parts corresponding to the number of poles in that series of magnets, d or d^1 , to which they are each of them attached, and so arranged that when revolving with the axis a fixed spring, h , will pass alternately on each of the longitudinally-projecting parts of g^1 and g^2 ; connecting it with one pole of the battery, while a similar spring, h^1 , placed as clearly shown in Fig. 6, connects the other terminal with the opposite pole of the battery; or, in other words, when the spring h is in connection with the terminal g^1 the spring h^1 is in connection with the terminal g^2 , and viceversa. On the shaft c pulleys i of any suitable configuration are secured, for the purpose of transmitting the motion to any other body by means of belts, &c., or worm or toothed gear-wheels may be used, if preferred.

Fig. 9 shows a plan of a simple commutator-switch for starting, stopping, or reversing the motion of the motor. In a plate, i' , of any suitable material, studs N N' P P' M M' are inserted passing through it; they are connected as follows: N N' to the negative pole of the battery, P P' to the positive pole of the battery, and M M' to the springs h h^1 , respectively. The studs above named are placed, as shown in the drawing, at equal distances from a common center, k , and equally apart from each other, while from the center k two or four plates of metal, k^1 , are fixed on arms l , of insulating material actuated by handle l' , by which the plates may be turned so as to connect N or P with M on one side, and N' or P' with M' on the other side. The plates k^1 must also be of such a size that they may rest on the two studs M M' without connecting or touching any of the others. Thus, when the motor is required to move in one direction, the plates k^1 are so placed that they connect the studs M M' with N' and P' , and to reverse the motion they connect M M' with P and N ; when required to stop the motion they are placed on M M' only.

Fig. 10 represents a section of a condenser similar to those used in connection with induction-coils, and applied for a similar purpose with motor to collect the electricity induced in the wire by the demagnetization of the iron cores at the instant of reversing the current or breaking the

circuit, and fully utilizing the battery power. This is constructed in the usual manner, viz.: A series of thin plates, of metal, such as tin-foil, are laid above each other with sheets of insulating material placed between each to prevent contact, the alternate sheets of metals being connected together at their opposite ends, and the ends of the condenser being attached to the springs h h^1 .

Fig. 11 represents a section of a governor for regulating the speed of the motor. It may be constructed on the shaft c , or made as a separate piece, as shown in the drawing, and placed anywhere in the electrical circuit. In this case it is constructed as follows: On the spindle q carried by bearings in any ordinary manner, a pulley, q^1 , is placed for causing it to revolve with the motor by a belt. To the spindle is secured a cylindrical piece of insulating material, q^2 , the spindle passing through its center. To the extremities of this are attached two metal rings, r r^1 ; to r are attached two springs, r^2 , as shown in the drawing, having their lower extremities loaded with any suitably-formed weights of metal, s , made to press upon the ring r^1 with greater or less force, as required, by adjusting the screws s^1 . To place this in the electrical circuit two springs, s^2 , are provided to each of the rings r r^1 , one on each side of them, and having one of their extremities pressing on the rings, while the other is suitably attached to any stationary part of the machine, and connected to a part of the electrical wire, which may be severed for that purpose.

The parts r^2 , s , s^1 , and s^2 are made in duplicate in the drawing, for the purpose of greater surety of connection, and forming an equilibrium to the spindle revolving at a high speed. When the speed of the motor is such that it causes the centrifugal force of the weights s to overcome the action of the springs r^2 , they press outward and become separated from contact with ring r^1 , and consequently break the electrical circuit.

Referring again to Figs. 1, 2, 3, 4, and 5, the series of magnets f f^1 are connected in the circuit of electricity anywhere between one of the springs h or h^1 and the battery. If desired, the electro-magnets f f^1 may be removed and permanent magnets used instead, or the series of magnets d d^1 may be permanent magnets, while those f f^1 are electro-magnets, the various other changes requisite, which will be well understood, being made.

The operation of the motor is as follows: A suitable galvanic-battery being provided and its poles attached to the simple commutator-switch, as described in Fig. 9, from thence the current passes to the springs h h^1 , and is by them transmitted, as hereinbefore described, to the magnets d d^1 , and having traversed the circuit of these in succession, (it being understood that each series of magnets acts separately,) then traverses in like manner the series of magnets f f^1 , (when the electro-magnets are used;) but not being acted upon by the compound commutator it always flows in the same direction. From these it passes through the switch, Fig. 10, to the other pole of the battery. By this means the magnets

$d d^1$ are attracted as they revolve to the magnets ff^1 , and as each of the poles in series d and d^1 pass these in ff^1 , the poles being reversed by the action of the compound commutator in the revolving magnets, their action is rendered double by attracting them as they approach, and repelling them immediately on passing. This may be better understood by reference to Fig. 5, in which the pole 1 of the magnet is attracted by the pole 2 and repelled by the pole 3, and so on all round the series.

Having thus described the construction and operation of our invention, to which we have given the name of double action electro-magnetic motor, what we claim as our invention, and wish to secure by Letters Patent, is as follows:

1. Two sets of magnets $d d^1$, each having their poles in a pair of soft-iron plates, d^2 , and all arranged upon a brass cylinder, c^1 , combined with corresponding sets of magnets $f f^1$, having their poles in soft-iron plates f^2 , and arranged upon rings $b b^1$, whose circumference is greater than that of cylinder c^1 , so that when the magnets d and f are opposite the magnets d^1 and f^1 are intermediate, as and for the purpose specified.

2. The insulating material g on shaft c , the two

pieces of metal $g^1 g^2$ not touching each other, the wire e , and pair of springs $h h'$, combined and arranged as a compound commutator, in the manner described, and for the purpose specified.

3. The plate i^1 , provided with studs $M M'$, $N N'$, and $P P'$ arranged thereon at equal distances apart and from the center k , and the pair of plates k^1 fixed on insulating arms l , when all are applied to springs $h h'$ and the negative and positive poles of the battery, to form an improved switch, as and for the purpose specified.

4. The magnets $d d^1$ and $f f^1$, having their poles in soft-iron plates $d^2 f^2$, the compound commutator $c g g^1 g^2 h h' c$, the switch $i M M' N N' P P'$ $k k' l$, the governor $q q^2 r r^1 r^2 s^2 s$, and the ordinary condenser, combined and arranged in an electrical motor, as and for the purpose specified.

5. The governor, composed of spindle g , cylinder q^2 , rings $r r^1$, springs r^2 and s^2 , and weights s , arranged and operating substantially in the manner and for the purpose described.
